CLAIM

The ornamental design for a headband with hair, as shown and described.

DESCRIPTION

FIG. 1 is a perspective view of a headband with hair showing my new design;

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines showing the head in FIGS. 1-7 illustrate environment and form no part of the claimed design. All other broken lines illustrate portions of the headband with hair that form no part of the claimed design.

1 Claim, 7 Drawing Sheets
